UNITED STATES PATENT OFFICE.

WILLIAM H. NUTT, OF NEWBURYPORT, MASSACHUSETTS.

SHOE HEEL.

Application filed January 5, 1924. Serial No. 684,510.

To all whom it may concern:

Be it known that I, WILLIAM H. NUTT, a citizen of the United States, residing at Newburyport, county of Essex, State of Massachusetts, have invented a certain new and useful Improvement in Shoe Heels, of which the following is a specification, reference being had therein to the accompanying drawings.

10. The invention relates to a new and useful improvement in shoe heels. Fancy shoe heels are frequently made of a body portion of wood or other solid material covered with either leather or fabric, or some other suitable material, making a dressy looking appearance. A very artistic and decorative appearance of the heel may be produced by a patchwork arrangement of two or more different colored leathers or other covering material, the several different colored materials being used on different parts of the heel and so arranged as to form a pattern of attractive design. If the different pieces of the colored material are simply laid on 25 the smooth surface of the heel with abutting edges in the manner of putting on wall paper, the edges of the different pieces where they abut against each other, are apt to peel somewhat, and even if they do not peel, 30 there is left a raw edge and if the covering is fabric, it will fray.

The object of the present invention is to so form the body of the heel and to so apply the covering portions that there will be no raw abutting edges and to securely hold the covering in place, and also to enhance the appearance of the heel. The invention consists in forming in the body of the heel, narrow channels or grooves along the boundary line between the several different portions which are to receive the different members of the covering and forming the several covering pieces with a sufficient margin so that when they are applied to the respective parts of the heel, said marginal portions will be tucked into the grooves. When the different pieces are cemented to the heel, and these marginal portions are tucked down into the grooves and cemented, the raw edges will 45 be entirely concealed and securely held.

The invention will be fully understood from the following description when taken in connection with the accompanying drawings, and the novel features thereof will be pointed out and clearly defined in the claims 55 at the close of this specification.

In the drawings:

Fig. 1 is a view in side elevation of the body of a heel formed with grooves ready to receive the covering. 60

Fig. 2 is a vertical section of the heel body shown in Fig. 1.

Fig. 3 is a developed plan of the blank for the marginal cover section.

Fig. 4 is a developed plan of the blank 65 for the central cover section.

Fig. 5 is a view in elevation of the finished heel.

Fig. 6 is a vertical section of the finished 70 heel.

Fig. 7 is a section on line 7—7, Fig. 6.

Referring now to the drawings there is shown in Fig. 1 the body of a shoe heel made of wood or other suitable solid material such as frequently used for heels of 75 ladies' shoes which are to be covered with leather, fabric or other sheet material. I mark out on the rear and side faces of the heel a design according to the pattern which is to be produced by the application of pieces 80 of covering material of different colors in the finished heel. I then form grooves in the body of the heel following the boundary or dividing line between the several pieces of the different colored material. In the 85 heel shown in the drawings, the pattern is of simple form intended for cover sections of two different colors. The pattern has a central panel 1 surrounded by a margin 2. A groove is formed in the body of the heel 90 along the dividing line between the centre panel 1 and the marginal portion 2. There is thus formed a groove 3 along the upper boundary line of the panel, a groove 4 at the bottom boundary line and grooves 5 and 95 6 at the side edges of the panel for the side boundary lines. The grooves 3 and 4 extend around to the opposite side of the heel from that shown in Fig. 1. There is also a groove 6 corresponding to the groove 5 100 on the opposite side. The covering pieces are blanked out with sufficient marginal extensions to lap over the edges into the grooves. In Fig. 4 there is shown a blank 7 die cut to the suitable shape to cover 105 the centre panel and having marginal extensions 8, 9, 10 and 11 of sufficient width to extend into the grooves. The blank for covering the marginal portion 2 of the heel is shown in Fig. 3. This blank is 110 cut out in its middle to allow for the panel covering already described, and has top.

bottom and side portions 12, 13, 14 and 15 respectively which are to cover the top, bottom, and sides of the marginal portion 2 of the heel. This blank also has inner 5 marginal extension portions 16, 17, 18 and 19 which are to fit into the four groove portions of the heel blank and has an outer marginal portion 20 which is to lap over the top or heel seat portion of the heel, 10 side marginal portions 21 and 22 which are to lap over onto the breast of the heel, and a marginal portion 23 which is to lap over onto the bottom of the heel. I apply the outer covering blank thus 15 formed to that portion of the heel for which it is intended, and tuck the inner peripheral marginal portions into the grooves and fold the outer marginal portions respectively over onto the top, breast and 20 bottom surfaces of the heel. Both covering members should be cemented to the body of the heel so as to firmly adhere thereto.

When the covering pieces are thus cemented to the heel, the tucked edges of the covering portions will all be concealed within the grooves and prevented from fraying.

Not only will the raw edges thus be protected so that there is no danger of peeling and fraying and they will wear better, but also an ornamental design is produced by the contour of the groove irrespective of the color of the material or 35 if all of the same color. It is preferred, however, to make the different pieces of material of contrasting colors or of different material and the artistic appearance of the design will thereby be still further 40 enhanced.

It is obvious that the design outlined by the groove may be varied as desired and two or more colors may be employed according to the character of the design.

45 The different sections of covering material may also, if desired, be made of different kinds of material of the same color;

for instance, one cover section might be made of leather and another section be made of silk or some other fabric. A contrasting appearance would be given to the different sections if made of different material even though of the same color. Even if all the pieces are of the same material and same color, the grooves with the tucked 55 in margins make an effective appearance whatever the design.

After the covering has been applied, a top lift should be attached to the bottom to protect the turned under marginal portion 23 of the cover and also to take the wear as usual for a top lift.

What I claim is:

1. A shoe heel having secured to its outer face a panel of thin sheet material which 65 has a marginal portion around its periphery engaged in a groove in the heel at some distance back from the top, bottom and side edges of the outer face of the heel and an independent border strip of 70 sheet material secured to the portion of the outer face of the heel which surrounds the said panel, said border strip having a marginal portion engaged in said groove.

2. A shoe heel having a covering of a 75 plurality of sections of sheet material on its outer face, the heel being formed with grooves along the boundary line between the different sections of the covering, the sections of the cover material having marginal portions which are tucked into said 80 grooves and secured therein.

3. A shoe heel having a covering of a plurality of sections of sheet material on its outer face, the heel being formed with 85 grooves along the boundary line between the different sections of the covering, the sections of the cover material having marginal portions which are tucked into said grooves, the different sections of cover material being of contrasting appearance. 90

In testimony whereof I affix my signature.

WILLIAM H. NUTT.
